UNITED STATES PATENT OFFICE.

WILBUR J. HEMPY, OF KANSAS CITY, MISSOURI.

BABBITTING JIG.

Application filed December 10, 1923. Serial No. 679,608.

My invention relates to improvements in babbittting jigs and while it may be used to advantage in babbittting various articles, in the present instance I have shown it arranged for babbittting connecting rods and main bearing caps.

One object is to provide interchangeable dies for accommodating bearings of different sizes, so that a large variety may be babbittted on the same jig.

A further object is to provide a jig of this character in which the working parts are arranged for speedy operation, so that a maximum number of bearings can be babbittted in a minimum period of time.

Other objects will hereinafter appear, and in order that the invention may be fully understood, reference will now be had to the accompanying drawings, in which:

Fig. 1 is a side elevation of the babbittting jig showing in dotted lines a connecting rod in position to be babbittted.

Fig. 2 is a front elevation of the babbittting jig with the bearing of the connecting rod in section.

Fig. 3 is a vertical section on line III—III of Fig. 2.

Fig. 4 is a plan view of the babbittting jig with the connecting rod removed.

Fig. 5 is a fragmentary irregular horizontal section on line V—V of Fig. 3.

Fig. 6 is a detail view of a bifurcated pin and one of the die nipples.

Referring now in detail to the various parts, 2 designates a frame which embodies a base 4, an upright portion 6 and a pair of standards 8.

10 designates a die having a chamber 12 communicating with inlet and outlet nipples 14 and 16, respectively, adapted to be connected to sections of hose, not shown. The inlet nipple 14 is for the purpose of admitting water to the chamber 12 to prevent the die 10 from becoming unduly heated and retarding the cooling of the fluid babbitt when poured into a bearing. The water escapes from the chamber 12 through the outlet nipple 16, which also supports the die 10 in vertical position at the upper portion of the frame 2, which is provided with an opening 18 through which said nipple 16 extends. The nipple 16 is provided with oppositely disposed grooves 20 to receive the prongs 22 of a bifurcated pin 24, which firmly holds the die 10 in the vertical recess 26 of the frame 2.

28 designates an interchangeable jaw slidably engaging the die 10 and supported by a movable holder 30 to which said die 10 is removably connected by a set screw 32. A 60 yoke 34 removably secured to the front side of the upright portion 6 of the frame 2 by stud bolts 36 and thumb nuts 38, is employed to support the holder 30 and the jaw 28 in proper relation to the die 10.

40 designates a lever for raising and lowering the holder 30 and the jaw 28. A pin 42 carried by the lower portion of the frame 2 serves as a fulcrum for the lever 40, the bifurcated forward end of which straddles 70 and supports a nut 44 adjustably engaging a screw 46 fixed to and depending from the lower portion of the holder 30.

The rear end of the lever 40 is provided with a hole 48 through which the lower end 75 of a toggle member 50 projects and is provided with a nut 52 between which and a coil spring 54 the rear end of the lever 40 is held. The toggle member 50 is secured by a pivot 56 to a handle 58 to which another 80 toggle member 60 is secured by a pivot 62. The handle 58 is mounted upon a pivot 64 carried at the upper ends of the standards 8. The toggle member 60 consists of two threaded elements whereby it may be 85 lengthened or shortened and is connected at its upper end by a removable pin 66 to the rear end of a lever 68 fulcrumed upon a removable pin 70 and provided at its forward end with a jaw 72 having a gate 74 90 coacting with a gate portion 76 in the upper part of the die 10 in directing the molten metal into the bearing A of a connecting rod B from which the cap has been removed.

The operation is substantially as follows: Initially the handle 58 is swung upwardly to the position disclosed by Fig. 1, which operation moves the jaws 28 and 72 apart, so that the bearing A of the connecting rod 100 B can be readily positioned upon the jaw 28 and into proper relation with the die 10, the front portion of which is concentric to but of less diameter than the inner surface of the bearing A to leave an intervening space C 105 to receive the Babbitt metal D. The face 7 of the upright portion 6 of the frame 2 constitutes a stop for the ends of the bearing A, as shown by Fig. 5.

The handle 58 is then lowered to the position disclosed by Fig. 3, which operation straightens out the toggle embodying the

members 50 and 60 until checked by a stop 79, and causes the levers 40 and 68 to move the jaws 28 and 72 toward each other and firmly clamp the bearing A. As the toggle 5 straightens out the spring 54 is compressed and compensates for any difference in movement between the levers 40 and 68 and also assists in holding the jaw 28 in engagement with the underside of the bearing A. In 10 order that the Babbitt lining may have flanges overlapping the lower and upper surfaces of the bearing A, recesses 80 and 82 are formed in the jaws 28 and 72, respectively. After the bearing A has been babbitted the connecting rod B is instantly released by throwing the handle 58 upwardly to the initial position, whereupon the jig is in position to receive another connecting rod to be babbitted. The water flowing through 15 the chamber 12 of the die 10 prevents the same from becoming unduly heated and retarding congealing of the poured babbitt, and hence the connecting rods may be babbitted as rapidly as they can be placed in 20 position to receive the fluid babbitt. The bearing caps which were previously removed 25 from the bearings A to permit babbetting thereof, may likewise be babbitted.

Change to another die of smaller or larger 30 diameter can be quickly accomplished by removing the yoke 34, which permits the nut 44 to be slipped out of engagement with the bifurcated forward end of the lever 40, thereby rendering the holder 30 accessible 35 so that a jaw of the desired diameter can be substituted for the jaw 28. The hose is then slipped off the nipples 14 and 16 and the pin 66 is withdrawn, after which the lever 68 is swung backwardly as indicated 40 by dotted lines Fig. 3, to loosen the pin 24 from the nipple 16, so that the die 10 can be removed and another of desired size substituted. The holder 30, the nut 44, the 45 yoke 34 and the pins 24 and 66 are then put back in place and the jig is ready for further operation. In some instances it may also be necessary to change the holder 30 and the lever 68 with its jaw 72, to accommodate dies varying considerably in diameter, but I have found in practice that dies 50 of different diameters within certain limits can have upper ends of one size, so that the same jaw 72 will answer for all.

From the foregoing description, taken in 55 connection with the drawings, it will be understood that I have provided a quick acting babbetting jig embodying the advantages above pointed out, and while I have shown and described the preferred embodiment of the invention I reserve the right to make such changes in the combination and arrangement of parts as properly fall within the spirit and scope of the invention as claimed.

Having thus described my invention, what

I claim and desire to secure by Letters Patent, is:

1. A babbetting jig consisting of a frame, a vertically positioned die supported by said frame and having a gate in its upper end, 70 a jaw movable in the frame and adapted to support a bearing in proper relation to the die to be babbitted, another jaw to coact with the first jaw in clamping the bearing, and toggle means connected to said jaws for 75 causing the same to clamp and release the bearing.

2. In a babbetting jig a suitably supported die, pivoted elements for holding a bearing in proper relation to said die to be babbitted, and toggle means connected to said 80 elements for causing the latter to simultaneously grip and release the bearing.

3. In a babbetting jig a suitably supported die, elements for holding a bearing in proper relation to said die to be babbitted, toggle means connected to said elements for causing the latter to grip and release the bearing, and spring means associated with said 85 toggle means to compensate for any difference in movement of the elements.

4. In a babbetting jig a suitably supported die, pivoted elements for holding a bearing in proper relation to said die to be babbitted, and means for simultaneously actuating 95 said pivoted elements and causing them to grip and release the bearing.

5. In a babbetting jig a vertically positioned die having a chamber therein with an inlet and an outlet for the circulation of a 100 cooling fluid, pivoted elements for holding a bearing in proper relation to said die to be babbitted and one of said elements having a gate for directing the fluid babbitt into the bearing, toggle means for actuating said 105 elements, and a handle for actuating said toggle means.

6. In a babbetting jig a frame having a hole therein, a die, a member projecting from said die through the hole in the frame, 110 a pin removably engaging said member to secure the die in place, a lever pivoted to the frame and having a jaw for holding a bearing in proper relation to the die to be babbitted said lever being adapted when reversed to loosen the pin so that it can be removed from the member, and an element 115 to coact with the jaw in holding the bearing in position to be babbitted.

7. A babbetting jig consisting of a frame 120 supporting a vertically-positioned die, levers fulcrumed at the upper and lower portions of said frame to swing in a vertical plane and equipped with jaws for holding a bearing in proper relation to the die to be babbitted, manually-controlled toggle means for actuating said levers and pivotally connected to one lever and having a loose connection with the other lever, and spring 125 means associated with said loose connection 130

to coact therewith in compensating for any difference of movement in said levers and their respective jaws.

8. A babbetting jig consisting of a frame for supporting interchangeable dies, an interchangeable jaw arranged to slidably engage one of said dies and adapted to support a bearing in proper relation to said dies to be babbitted, a holder for said jaw having a depending threaded element, a lever fulcrumed on the frame, a nut mount-

ed on said lever and adjustably engaging said threaded element, a second lever fulcrumed on said frame and equipped with a jaw to coact with the above-mentioned jaw 15 in holding the bearing, and manual means for simultaneously actuating said levers to effect the holding and releasing of the bearing.

In testimony whereof I affix my signature.

WILBUR J. HEMPY.
